202,769

VACUUM CLEANER

Earle E. Witham, P.O. Box 533, Montpelier, Vt.

Filed Mar. 15, 1965, Ser. No. 84,251

Term of patent 14 years

(Cl. D9—2)

FIGURE 1 is a front elevational view of a vacuum cleaner showing my new design;

FIGURE 2 is a top plan view of the vacuum cleaner;

FIGURE 3 is a side elevational view thereof, the opposite side is identical;

FIGURE 4 is a rear elevational view of the vacuum cleaner.

I claim:

The ornamental design for a vacuum cleaner, as shown and described.
